HAND TOOL FOR INSERTING INSULATING STRIPS

Frank S. Kundtz, Cleveland, Ohio, assignor to Jack & Heintz, Inc., Bedford, Ohio, a corporation of Ohio

Application September 25, 1944, Serial No. 555,743

1 Claim. (Cl. 29—270)

This invention relates to hand tools and has for its object to provide a simple, inexpensive, compact and efficient hand tool that will be suitable for inserting members in inaccessible openings such as inserting thin fragile and bendable insulating paper strips between adjacent stator coils or the like in electrical devices.

It is necessary to insert these thin strips of paper-like insulation between these closely adjacent coils and it is tedious and time consuming, if not impossible to manually push flexible paper strips between the coils because the strips bend, wrinkle or break due to their lack of structural stiffness.

To this end it is proposed to provide a hand tool comprising a tubular barrel having a slidably rod therein. The barrel has a thin metallic strip anchored to the closed end of the barrel and extending past the open end thereof. The rod is formed with a slot the full length thereof to slidably receive the metallic strip. The rod at its outer end is bevelled to form a wedge to be inserted between the coils while the rod is in extended position, with a single insulating strip in the slot in the rod, the outer end of the insulator being flush with the outer end of the rod and the inner end resting on the outer end of the metallic strip. The wedge acts as a spreader for the coils and a manual retraction of the rod into the barrel causes the metallic strip to act as a plunger to push the insulating strip to its full length between the coils without fracture or bending. Other features will appear in further detail in the following specification and appended claim and in the accompanying drawing, in which:

Figure 1 is a view in longitudinal section taken through the hand tool showing the sliding rod in extended position in the barrel with the insulating strip within the slot and the plunger for pushing the strip in retracted position prior to insertion between the stator coils;

Figure 2 is a view similar to that of Figure 1 taken at right angles thereto; and

Figure 3 is a view in longitudinal section taken through the barrel of the tool from the same angle as Figure 2, showing the plunger in side elevation and in retracted position in the barrel;

Figure 4 is a view in section taken along line 4—4 of Figure 1;

Figure 5 is a view in section taken along line 5—5 of Figure 2; and

Figure 6 is a view in front elevation of the device as viewed in Figure 3.

Referring more particularly to the drawing,

the hand tool may comprise a barrel 1 closed at one end by an internally fitted plug 2 which is transversely slotted to receive the inner end of a strip of metal 3, the plug and strip being further anchored to the barrel by a pin 4 extending through the barrel, plug and strip. Arranged interiorly for longitudinal movement within the barrel is a rod 5 with an enlarged flange 6 for sliding engagement with the larger bore of the barrel while the smaller bore receives the rod for sliding engagement. The shoulder 7 forms a limit for outward movement of flange 6 while the inner limit is the plug 2.

The rod 5 is formed with a longitudinal slot 8 extending the length of the rod. This slot is formed by cutting through one side of the rod and plugging up the open side with a metal filler strip 9 retained therein by pins 14. The resulting slot 8 is sufficiently wide to receive the plunger strip 3 in sliding relation as well as the insulating strip 10 which is of the same width and thickness as the plunger strip 3.

The rod, at its outer end is tapered at 11 to provide a wedge shaped point and on one side is 25 recessed to form an abutment shoulder 12, while the other side is tapered at 13. The filler strip 9 extends rearwardly from the abutment shoulder 12 toward the right the remaining length of rod 5.

30 In operation, the rod 5 is pulled into extended position, as shown in Figures 1 and 2, and the insulating strip loosely inserted in slot 8 of the rod until its lower end abuts the forward end of the plunger strip 3 and its outer end is flush with the outer end of the slot past the abutment 12 and the outer end of filler strip 9 so that it may be visible for this portion of its length.

The wedge end of the rod 5 is then inserted 40 between the stator coils of the electrical device to a limit prescribed by the abutment shoulder 12. This temporarily spreads the stator coils sufficiently for the desired purposes. The barrel 1 within the grasp of one hand of the operator is then shoved forward. This brings about a retraction of the rod 5 within the barrel. As this occurs the flexible metallic strip 3 rides relatively forwardly in slot 8 of the rod and acts as a plunger to insert the insulating strip 10 between the coils in the space made temporarily 45 ample for such purposes by the spreading action of the rod wedge tip.

From the foregoing it will be seen that there has been provided a simple and inexpensive hand tool whose wedge tip may be readily inserted between closely adjacent stator coils to temporarily

spread them sufficiently to receive a thin frangible insulating strip. Moreover, a simple operation of the tool to bring about relative movement between the barrel and the rod completes the insertion of the insulating strip in its proper place without damage to the strip. The recessed portion providing the abutment shoulder 12 also makes visible the outer end of the insulating strip. The slot 8 is easily formed in the bar by cutting the rod and the subsequent closing of 10 the same by the filler strip.

I claim:

A tool of the character described comprising a hollow barrel and a rod mounted to be slidable therein, a metallic plunger strip anchored to said barrel, said rod being longitudinally slotted to receive said plunger strip for its full length when said rod is in retracted position within said barrel, said rod being adapted when in extended position to receive an insulating strip of approximately the same width and thickness of the plunger strip and of a length determined by the

distance between the outer end of the plunger strip and the outer end of said slot, said rod having its outer end tapered to provide a wedge for manual insertion and spreading stator coils of an electrical device stator, said tapered end being cut away to provide an abutment shoulder for said stator coils, said plunger strip, upon retraction of said rod within said barrel, being adapted to force said insulating strip freely into a position between said stator coils temporarily spread apart by the wedge action of said tapered forward end of said rod, said slot in said rod being cut through one side wall thereof and covered by a filler strip of a length extending from said abutment shoulder to the inner end of said rod leaving said slot in the side wall open from said abutment shoulder to the tip of said tapered portion for inspection purposes to determine whether the insulating strip is in the tool prior to operation of the tool.
